PACKING MATERIAL

Charles K. Dillingham, Plainfield, N. J., and Phillip D. Cannon, Philadelphia, Pa., assignors to Johns-Manville Corporation, New York, N. Y., a corporation of New York

Application October 15, 1932, Serial No. 637,952

1 Claim. (Cl. 154—45.5)

This invention relates to a packing material and particularly to one adapted for use as a gasket between plane surfaces.

The invention comprises a woven, heat-resistant 5 ant, gasketing material containing a central portion woven integrally with the outer portions and adapted to be more readily penetrated by a conventional fastening element than the said outer portions.

10 The invention is illustrated in the drawing, in which

Fig. 1 shows a front view of a preferred form of gasketing tape with the yarn removed from some of the reenforcing wires, for clearness of 15 illustration; and

Fig. 2 shows a front view of a similar tape with the central portion cut out at intervals, to provide open spaces.

In the figures, there is shown a tape with outer 20 portions 1 adapted to contact closely with surfaces that are to be packed and a central portion 2 that is adapted to be penetrated by fastening means, such as a bolt, more readily than the adjacent outer portions.

25 The outer portions contain both longitudinal or warp strands 3 of yarn and transverse or filling strands 4 interwoven therewith. The central portion contains a smaller number of strands per unit of area or length than the outer portion.

30 The embodiment illustrated, contains strands extending in one direction only, namely, transverse or filling strands 4. Furthermore, the filling strands in the form illustrated are spaced farther apart, that is, are less numerous per unit of length of the tape, than are the filling strands in the outer portions.

35 The yarn used is preferably heat-resistant. We have used to advantage asbestos yarn which, in the strands constituting the warp, is relatively 40 soft and not wire-reenforced, and, in the strands composing the filling, may contain wires 5, such as fine brass wire which is frequently used to reinforce asbestos yarn.

45 As used, the tape is impregnated with a suitable packing or friction compound 6, such as a conventional one containing a large proportion of rubber and a vulcanizing agent.

To make the insertion of large bolts or fastening means through the central portion very convenient, the central portion may be cut out at 50 intervals, to provide the spaces 7 positioned to correspond to the locations of the bolts or other fastening means in a gasketed assembly.

55 The method of manufacturing the product of the invention is illustrated below, in the case

of a gasketing tape suitable for use in gasketing the head plate of a locomotive.

The weaving is done by a loom including in the 5 assembly a yarn beam, two or more harnesses for the warp strands, a reed, a shuttle, and a cloth beam, in addition to the usual accessories and driving means. The strands that are to compose the warp in the finished fabric are spaced by the harness mechanism or otherwise into two parallel bands that correspond to the outer portions 1 in the finished tape, to leave a space or gap between them, in what is to be the central portion of the 10 woven product. The filling strands are woven with the spaced bands of warp yarn. When it is desired to space the filling strands farther apart 15 in the central than in the outer portions, the outer bands of warp threads may be alternately depressed or elevated so that the shuttle carrying the filling yarn engages and interweaves the filling 20 yarn with the warp yarn in one of the said bands only, during selected passages of the shuttle. For example, the loom may be operated so that the shuttle weaves the filling strand with both of the spaced bands of warp yarns, then with only the right of the said bands, then with both 25 bands, then with the left band only, then with both bands, and so on, to give a relatively open structure in the central part of the tape. It is considered unnecessary to illustrate the loom, inasmuch as it is conventional.

30 After the tape is woven, it is calendered, to smooth the surfaces and adjust the size and shape, and then is impregnated with suitable material of type commonly used to impregnate a gasket or packing. Thus the tape may be passed through a 35 solution of rubber and vulcanizing agent therefor in a volatile solvent and the volatile solvent later removed by evaporation.

When the tape is to be used for gasketing under 40 conditions of elevated temperature, it is not necessary to vulcanize the tape before it is installed for use, inasmuch as the prevailing temperature during use will cause vulcanization. However, if desired, the tape may be subjected to an elevated 45 temperature for a substantial period of time adapted to cause vulcanization of the rubber before the tape is offered or installed for use.

The use of the tape in packing may be exemplified by the case in which the tape is installed as 50 a gasket between two plane surfaces, held together by fastening means including, for example, a bolt which passes through the gasket and through the elements provided with the said plane surfaces. The filling strands in the central portion of the 55 tape are spread apart to form a space through

which the fastening means are inserted. Then the surfaces to be gasketed are caused to contact closely with the gasketing material, as by tightening the bolt.

5 The gasketing tape has several important and novel features. The strands which pass through the central portion are continuous with corresponding strands in the outer portions. Further, these strands are strong when wire-reinforced and serve to hold the outer portions tightly in position. Since they extend practically at a right angle to the length of the tape, they establish the spacing of the outer portions of the tape from each other and prevent excessive spreading apart of 10 these portions under all circumstances. When the strands in the central portion are spread apart to allow for the insertion of a bolt or the like therethrough, the central portion around the bolt still remains relatively thin; there is thus provided a 15 distinct advantage over conventional types of tape gasket in which a very thick portion of the gasket around the fastening bolt may be produced by spreading apart closely woven gasket material to allow the insertion of the bolt therethrough. The 20

central portion, as well as other portions in the preferred product, are heat-resistant and, at the same time, are compressible, non-corroding, and resilient.

The details that have been given are for the purpose of illustration and not restriction, and many variations therefrom may be made without departing from the spirit and scope of the invention.

What we claim is:

A packing tape comprising longitudinally extending strips of woven fabric constituting the outer portions of the tape and filler strands integrally woven with the said strips and securing them together in spaced relationship, some of the 15 filler strands extending through the space between the strips and being arranged in the said space as a plurality of series containing each relatively closely spaced strands and being spaced from the next of the said series, to provide a space adapted to receive fastening means of the type of a bolt.
